LUIGI TOCCO AND MICHELE LANDI, OF PARIS, FRANCE, ASSIGNORS TO SOCIETE "LE FOUR CHIMIQUE ROTATIF" (SOCIETE ANONYME FRANCAISE), OF PARIS, FRANCE.

ROTARY CHEMICAL FURNACE.

Application filed June 22, 1926, Serial No. 117,874, and in Italy June 26, 1925.

Our invention relates to improvements in continuously operating rotary chemical furnaces of the type in which the materials to be treated are moved through the various 5 stages of the furnace by the action of gravity.

One of the objects of the invention is to provide a furnace of the character indicated which shall be capable of general use in the 10 chemical industry for producing a transformation of complex ores or minerals, such as metals, metalloids and their combinations in a continuous cycle. Our invention also 15 contemplates the treatment of other chemical substances in a continuous cycle even where the reactions produced involve conditions differing considerably from one another.

Another object of the invention is to provide 20 an improved electric heating arrangement for the furnace.

Still another object of the invention is to provide means for utilizing the excess 25 heat generated by the various reactions for producing energy in the form of steam, whereby the fuel consumption is partially compensated for.

Our invention is further comprised in certain 30 novel forms, construction, and combination of parts, the objects of which are to provide reliable devices for the purposes stated and to cheapen the cost of manufacture by simplifying the construction all of which will hereinafter be fully described 35 and claimed.

Other objects of the invention will be obvious to those skilled in the art with reference 40 to the accompanying drawing forming part of this specification, and in which—

Fig. 1 is a fragmentary sectional view of 45 the furnace;

Fig. 2 is an end view of the furnace with parts broken away showing certain details; and

Fig. 3 is a detail partly in section showing 50 the driving mechanism of the furnace.

A hopper 1 is provided above the furnace for receiving the materials to be treated which pass from there to a crushing device 55 2 also situated above the furnace. Extending from the crushing device 2 is a conduit 3 opening into a distributor 4 through which the said materials pass. The said distributor 4 is operated by a train of gearing 5 driven by a shaft 6 and a pinion 7. The

pinion 7 meshes with a toothed ring 8 mounted on the rotatable cylindrical body 20 of the furnace I thereby insuring synchronous driving of the feeding mechanism and the automatic regulation of the feeding 60 of the materials to be introduced into the furnace.

Leading from the distributor 4 is a tube 9 which connects with a second distributor 10. The said distributor 10 is connected to 65 the interior of the furnace I by means of a tube 11 through which the materials fall into the first zone I_r of the furnace I. The furnace I rotates about a fixed head A which is mounted on a supporting base 15. 70 Mounted on said head are a pair of brackets 13 and 14 carrying the feeding and distributing apparatus above described.

A pair of armoured conduits 17 extend 75 through said head for a purpose to be subsequently pointed out and are fastened thereto by means of clamping nuts 16. A hermetic closing ring 18 is disposed between the rotary portion 20 and the fixed head A for preventing the escape of gas and vapors. 80 The cylindrical portion 20 of the furnace is faced with a metal disc 19 and is lined with a refractory material 21. An aspirator 22 having a bell at its extremity projects through the head A into the zone or 85 chamber I_r for the purpose of drawing off the water vapor given off by the materials while passing through the said chamber during the drying thereof.

The rotary portion 20 of the furnace I is 90 guided laterally by means of a number of sets of rollers 25' (Fig. 2) and longitudinally by means of rollers 25 mounted on supports 26. Each of the said rollers 25 bears against an iron ring 23 mounted on an expandable support 24 carried by the cylindrical element 20.

The end of the first zone I_r terminates in a diaphragm 27 arranged to allow the material under treatment to pass by as indicated by the arrow K, and enter the second zone I_x on the opposite side of said diaphragm.

The rotary element 20 carries a toothed ring 28 with which meshes a pinion 29 105 mounted on a shaft 30 to which is keyed a driving gear 31 meshing with a gear 32 driven by a pulley 33 and a belt 34 (Fig. 3).

The second zone I_x terminates in a diaphragm 37 similar to diaphragm 27 and 110

arranged to allow a passageway 36 between said zone and a third zone I_y on the opposite side of diaphragm 37.

One of the pipes 17, above mentioned, extends clear through the furnace and is provided with a screw conveyor 35 for introducing pulverized carbon into the end of the second zone. The carbon falls into the diaphragm 37 and mixes with the materials as they pass through the passage way 36 from the second to the third zone.

The tube 17 containing conveyor 35 projects through the fixed head A and is provided at its extremity with a charging hopper 38. The shaft of the screw conveyor 35 projects through its tube 17 and is coupled to a suitable driving mechanism shown diagrammatically at 39.

The second of the tubes 17 contains an air pipe 40, provided with a blast nozzle 42 projecting into the zone I_x for supplying air thereto. Carried by the same pipe is a pyrometer 41 for checking the temperature.

In the wall of the rotary member 20 adjacent the zone I_y are provided a plurality of heating resistances 43 mounted in crevices 44 provided in the said wall. The said resistances are ordinary electrical heating elements and are protected from oxidation and insulated by means of oxide of zirconium tamped into the said crevices in such a manner as to completely surround the said resistances. Resistances 43 are supplied with current by means of a plurality of copper collector rings 46 mounted on the rotary element 20 of the furnace by means of supports 47, as shown in Fig. 1.

Arranged to bear on the said rings are a plurality of brushes 48 (Fig. 2) each receiving current by means of a cable 51 connected thereto. Contact is made between the resistances 43 and the rings 46 by means of a plurality of conductors 55.

The zone I_y terminates in a fixed head A' similar to the head A about which the member 20 rotates. Extending through said head is an aspirator tube 56 opening into the reaction chamber I_y for recovering the gaseous products of combustion. The extremity of member 20 is provided with a facing 19' and a cooperating hermetic sealing ring 18' similar to the corresponding elements previously described with respect to the opposite end of the section I of the furnace.

So far the description has been limited to the said section I. Beneath said upper section is disposed a second inclined furnace section I_z , in which further reaction of the materials being treated takes place.

A conduit 57 communicates with the chamber I_y of the upper section I through the fixed head A' . The conduit 57 is provided in its lowermost side with a grid 58 and a collecting chamber 59 disposed there

beneath. Communicating with the chamber 59 is a discharge tube 60. The lead for example contained in the complex ore undergoing treatment falls into the chamber 59 and is drawn off through the tube 60. The material remaining on the surface of the grid is adapted to fall through a continuation 61 of conduit 57 surrounded by a water jacket 61' through which water is circulated through the pipes 62, 63. The extension 61 75 communicates with a water-cooled device for separating the iron oxide of the material undergoing treatment shown diagrammatically at 64 and provided with a water jacket 65 fed by means of water circulating pipes 66, 67.

The lower section I_z above mentioned is in general similar to that of section I previously described. The driving mechanism, the guiding rollers and the arrangement of 85 the heating elements and their cooperating parts is identical with that described in connection with the upper section I and since these elements have been given the same characters of reference they need no further 90 comment. The said lower section I_z , however, is divided into two reaction chambers O and Q whose walls are independently rotatable about a fixed head common thereto which will be subsequently described more 95 in detail.

The separating device 64 communicates with the chamber O of the section I_z by means of a pipe 69 passing through a water-cooled head A_z forming a tight joint with 100 the furnace wall 73 of refractory material by means of a hermetic ring 70 and a facing ring 71 similar to the arrangement previously described.

Disposed within the chamber O is an ordinary multitubular boiler shown diagrammatically at O' (Figs. 1 and 2) having an extremity projecting through the head A_z and provided with a steam collecting pipe 74 and a water feed pipe 75. Extending 110 through the head A_z are also an aspirator tube 76 for drawing off sulphurous acid and an air inlet pipe 77 both communicating with the chamber O.

The rotary element 73 is faced with a plate 115 79 hermetically sealed by means of a ring 79' to a fixed water-cooled head 80. Fixed to said head is a support 78 upon which is carried the inner end of the boiler O'.

The material is adapted to pass through 120 a series of openings 83 in a triturating device shown diagrammatically at 84, 85 carried by said head 80. Said triturating device communicates with a conduit 86 through which pulverized carbon is injected into the 125 material passing therethrough. The triturating device is operated by a shaft 88 driving a pinion 89 connected to said device.

The fixed head 80 is of cellular structure as shown at 90 is adapted to have a cooling 130

fluid circulated therethrough. Said head is also provided with an air inlet pipe 92 provided at its extremity with a blast nozzle 93 opening into the chamber Q (Fig. 1).

5 The cylindrical rotatable wall surrounding the chamber Q is fastened to the head 80 in precisely the same manner as member 73. The lower end of said wall is faced by a plate 97' and rotates about a water-cooled head 97, a hermetic ring 98 being interposed as previously described.

10 The lower end of the fixed head 97 is provided with a discharge opening 100 opening into a conduit 99 communicating with a conveyor 101. Associated with said conveyor is a hot air aspirator pipe 102. Projecting through the head 97 and communicating with chamber Q is an aspirator tube 103 for drawing off zinc vapors.

15 20 In operation the mineral to be treated is triturated and mixed with a flux in the proper proportions and introduced into the hopper 1. The distributing mechanism associated with said hopper assures an automatic feeding of the said material into the furnace since it is driven by the rotating member of the furnace.

25 30 The diameter of the upper and lower sections of the furnace, their inclination, the length of each reaction chamber and the speed of rotation are so chosen that the mineral undergoing treatment will be retained in each zone for a period of time necessary to produce the required reaction. The inclination of each section of the furnace and their movement keeps the mineral constantly in motion which movement is aided by the inertia of the material and thereby exposes all the surfaces of the particles of material 35 40 undergoing treatment to each successive reaction.

45 The temperature of the first zone I_r is maintained in the neighborhood of 150° C. nothing more taking place in this zone than the driving off of the moisture in the mineral through the suction pipe 22.

50 55 The mineral is then moved into the second zone I_x where air is added through the blast pipe 42. The temperature of the second zone is maintained at about 380° C. and an endothermic reaction is produced such as, for example:

60 65 The material undergoing treatment then passes into the third zone I_y, carbon being added as it passes by the diaphragm 37. The temperature of this zone is maintained at about 500° C. and a second endothermic reaction takes place which according to our example is:

65 70 The carbon monoxide is drawn off through

the pipe 56 and the lead is collected in the collector 59 as already mentioned.

70 It will be noticed that once the furnace is in operation it is an easy matter to regulate the temperature of the whole three zones by cutting out or adding electrical resistances 43 which due to their successive disposition permits of a gradual increase in temperature in the third zone if desired by using resistances of different heating characteristics.

75 The mineral remaining on the grid 58 passes through the separator 64 of the electro-magnetic type which is too well known in the art to require a detailed explanation 80 as the particular type forms no important part of this invention. In the said separator iron in the form of (Fe₃O₄) is recovered from the mineral undergoing treatment.

85 The material remaining in the separator is led into the fourth zone O in the lower section of the furnace which is maintained at about 600° C. Here an exothermic reaction takes place which might be for example:

90 In this zone a complete roasting of the blend takes place and air is introduced through the pipe 77 for producing a transformation into oxide in order to liberate the SO₂ which is drawn out as fast as it is given off through the pipe 76. The recuperating boiler O' disposed in this zone not only permits the 100 temperature of the zone to be regulated but also affords a means of recovering the excess heat of the reaction. This boiler is preferably covered with a refractory envelope (not shown) for protecting it from the SO₂ fumes. The purpose of the head 80 is to prevent the SO₂ from being drawn into the 105 fifth zone Q. The triturating device 84, 85 carried thereby is destined to prevent agglomeration of the mineral passing into zone Q and to regulate the quantity thereof 110 passing through. During the passing of the said mineral into the zone Q the proper amount of carbon is added through the pipe 86.

115 In the fifth and last zone Q the material passing therein is subjected to a temperature of about 1400° C. which is maintained and regulated by means of the resistances 43 similar to those in the third zone I_y. The reactions which take place, according to the 120 example chosen are as follows:

125 Air is introduced into this zone through the pipe 92 for producing oxidation of the zinc vapors as given in the above formulae. The zinc vapors are led off through the pipe 103 and the CO is separated therefrom by any of the apparatus well known in the art. The 130

zinc oxide is collected by the well known condensing process and the CO gas is utilized for any of the well known uses.

Finally the residue passes through the opening 100 on to the conveyor 101 and the surplus heat given off thereby is lead through a pipe 102 for utilization such as producing steam. If the said residue contains a sufficient quantity of CaO and MgO it may be hydrated with water and utilized for building blocks as is well known in the art.

Having thus described our invention what we claim as new and desire to secure by Letters Patent is:—

- 15 1. In a continuous operating rotary furnace of the character described, having two fixed heads, a rotatable element disposed between said heads and means associated with said heads for introducing and withdrawing the materials to be treated, the combination of auxiliary apparatus and means driven by said rotary furnace for automatically operating said auxiliary apparatus in accordance with the speed at which said rotary furnace is driven.
- 20 2. A continuous operating rotary chemical furnace having two fixed heads, means carried by said heads for taking off the gases of reaction formed at different points remote from said heads and means for introducing the materials to be treated at predetermined points in said furnace as desired.
- 25 3. In a continuous operating rotary chemical furnace, two fixed heads disposed at the ends of said furnace and a plurality of fixed diaphragms disposed in the interior of said furnace for dividing it into several reaction chambers carried by said heads.
- 30 4. In a continuous operating rotary chemical furnace, two fixed heads disposed at the ends of said furnace and a stationary boiler carried by said heads for recovering excess heat and cooling the said furnace during operation thereof.
- 35 5. In a continuous operating rotary chemical furnace, two fixed heads disposed at the ends of said furnace, a rotatable element disposed between said heads, a plurality of electrical resistances disposed in the interior of said rotatable element for heating and maintaining the quantity of heat desired, supports mounted on the periphery of said ro-

tatable element, a plurality of insulated contact rings mounted on said supports, there being one ring for each of said resistances, means for electrically connecting said rings to said resistances, fixed brushes contacting with said rings and means for supplying an electro-motive force to each of said brushes for the purpose described. 55

6. In a continuous operating rotary chemical furnace, two fixed heads disposed at the ends of said furnace, a rotatable element disposed between said heads, said rotatable element constituting the wall of the furnace, a plurality of crevices disposed on the interior of said wall and a plurality of electrical resistances disposed in said crevices whereby the temperature may be uniformly regulated to the extent desired. 60

7. In a continuous operating rotary chemical furnace, two fixed heads disposed at the ends of said furnace, a rotatable element disposed between said heads, crevices carried on the interior of said rotatable element, a plurality of electrical resistances disposed in said crevices for uniformly regulating the temperature of the furnace to the extent desired, supports mounted on the periphery of said rotatable element, a plurality of insulated contact rings mounted on said supports, there being one ring for each of said resistances, fixed brushes contacting with said rings and means for supplying an electro-motive force to each of said brushes for 70 the purpose described. 75

8. A continuous operating rotary chemical furnace as set forth in claim 7 in which the resistances are insulated from the interior of the crevices and protected from 80 oxidization by means of oxide of zirconium.

9. In a continuous operating rotary chemical furnace, two fixed heads disposed at the ends of said furnace, a third fixed head disposed intermediate said first mentioned heads for dividing said furnace into a plurality of reaction chambers and a stationary boiler supported by one of said first mentioned heads and said intermediate head for recovering excess heat and cooling the said 100 furnace during operation thereof. 95

In witness whereof we affix our signatures.

LUIGI TOCCO.

MICHELE LANDI.
